FIG. 1 is a front view of our new design relating to a fitting for tyre inflation and tyre repair;

FIG. 2 is a rear view of our new design;

FIG. 3 is a left side view of our new design;

FIG. 4 is a right side view of our new design;

FIG. 5 is a top view of our new design;

FIG. 6 is a bottom view of our new design; and,

FIG. 7 is a perspective view of our new design.

The broken line showing of the arrow in the gauge is included for the purpose of illustrating portions of the fitting for tyre inflation and tyre repair and forms no part of the claimed design.
